UNITED STATES PATENT OFFICE.

ALEXANDER S. SPEER, OF BUFFALO, NEW YORK, ASSIGNOR, BY MESNE ASSIGNMENTS,
TO CENTRAL TRUST COMPANY OF ILLINOIS, A CORPORATION OF ILLINOIS, AND
AKSEL K. BODHOLDT, OF EVANSTON, ILLINOIS.

APPARATUS FOR PRINTING DESIGNS.

Application filed February 9, 1921, Serial No. 443,513. Renewed July 9, 1923.

My invention is an improvement in apparatus for impressing trademark designs, and relates to that character of apparatus especially designed for use with materials which 5 in finished form are of a soft and gummy nature and which may have a protective coating on one face.

Among other objects, the invention is intended to provide a novel and improved apparatus for applying trademarks, designs or other identifying data to composite sheet materials, such as composite asphalt roofing or the like, which are distinct and cannot be readily obliterated but which nevertheless do 15 not result in marring or disturbing the opposite face of the material.

The character of the invention may be best understood by reference to one illustrative apparatus embodying the invention and 20 shown in the accompanying drawings.

In the drawings;

Figure 1 is a side view of a machine for making prepared roofing,

Figure 2 is a front view of the printing 25 roller and its supporting mechanism,

Figure 3 is a plan view of the same,

Figure 4 is a detail section through the die,

Figure 5 is a detail section through the 30 compressing rollers,

Fig. 6 is a similar view at right angles to Fig. 5.

I shall explain the use of the illustrative apparatus in connection with asphalt roofing, 35 which is one kind of material to which the invention applies. For this purpose I have illustrated diagrammatically apparatus for making asphalt roofing and have indicated one arrangement for conveniently employing 40 my invention in connection with such apparatus. It will be obvious, however, that the invention is not limited in its use to this particular arrangement or with apparatus of this character.

45 In the preparation of prepared roofing, composed of an absorbent felt-like base or body saturated with a waterproofing and adhesive compound, and provided on one face with a non-adhesive surface layer such as a 50 protective coating of crushed stone or the like, it is desirable that the sheet or web of roofing be provided with trademark designs, and that these designs be upon the reverse face of the sheet or web, that is upon that

face which will be hidden when the roofing is in use. It is also desirable that such designs be not visible on the weather face of the roofing. I have found it very difficult to impress such designs on the finished sheet or web, because of the fact that some mark of 55 the design appears on the weather side, and this regardless of how much care is exercised in the impressing of the designs. In this illustrative instance, the impressions are made on the base or body of the web or sheet, 60 and before such web or sheet receives the protective coating. Preferably I make the impressions before the web is saturated with the waterproofing and adhesive compound, 65 because of convenience in manufacturing, 70 but it is possible to make the impressions after the saturation of the sheet or web, and before the application of the protective coating.

In the present embodiment of the invention, the web 1 of absorbent material, which in practice is of a felt-like nature, is supported upon a reel 2. The web is passed between a pair of rolls 3 and 4, the roll 3 being a platen roll, while the roll 4 is a printing roll, carrying dies which impress the designs on the under face of the web. From the rolls 3 and 4, the web is passed through a solution of waterproofing and adhesive material, as for instance asphalt, held within a tank 5, the web being guided through the tank by direction elements 7 in the form of rollers. It will be obvious that the web may be retained in the solution as long as may be necessary to thoroughly saturate the 75 same with the waterproofing and adhesive solution, and as it leaves the solution it is engaged by compressing rollers 8 and 9, which express the excess solution from the web. These rollers are arranged above the 80 tank, so that the excess solution flows back into the tank. After the web passes rolls 8 and 9 it is customary, though not necessary, to apply a protective coating such as 85 heavy asphalt to the wearing side of the material. This coating may be of any desired thickness, governed by the space between the rolls 10. Ordinarily no coating is placed on the opposite side of the web. Since the saturating or preserving compound and the 90 coating are of an adhesive character, it is desirable to apply a coating of powdered or crushed mineral to the surfaces of the web 95 100 105

so that the material may be handled without danger of sticking together. If desired, a wearing surface of crushed stone or the like may be placed upon the asphalt coating not only to stabilize this coating but to give to the material a pleasing appearance. This crushed material may be suitably applied to the web from the hopper 11. It will be understood that the asphalt coating applied to the web and the crushed stone or the like are applied to the surface of the web opposite that bearing the impressed designs. From the coating rollers the web passes to the finishing machine, where it is cut into strips, 15 or into shingles, as may be desired.

It might be thought that the impressed designs would disappear under the pressure of the compressing rollers, but this is not the case. I have found that instead of obliterating the designs, they are made deeper by the compressing rollers, because of the fact that they are filled with an excess of solution as they pass between the rollers, and such solution is trapped in the impressions. Since 25 the saturating solution is incompressible, the pressure applied thereto by the passage of the web around the roll, is transmitted to the web and tends to deepen the impressions therein. In other words, while the web itself may be compressed in passing over the roll 8, for example, the saturating compound trapped in the depressions cannot be compressed and thus the pressure exerted upon the web in the regions of the depressions is 30 concentrated upon the web in this region and thus tends to deepen the depressions rather than obliterate them. Approximately what takes place is illustrated in Fig. 6, in which the dark cross-sectioned areas represent the 35 solution trapped in the depressions as the web passes over the roll 8. After the web leaves the compressing rollers, the liquid which fills the indentations of the impressions is absorbed by the base or body, leaving 40 a clearly impressed design. After the application of the protective coating, which covers the weather side of the web, there is no possibility that any mark or indication of the 45 design could be visible through such protective coating. The solution before drying, as well as after drying, cements those fibers of the felt closely together which have been 50 displaced by the characters of the die, and after the solution has dried, such fibers are 55 firmly held, so that they cannot re-act to lessen the clearness of the design.

The dies 12 which make the impressions are held in recesses 13 provided in the peripheral surface of the printing roll, and 60 they are held by set screws 14. The roll is mounted on a shaft 15, which is held in the arms 16 of a yoke. The body 17 of the yoke is journaled on a shaft 18, which is supported by a bracket 19, connected to a suitable support 20 by bolts and nuts 21. The shafts 15

and 18 are connected to the yoke by tapering pins 22, and the printing roll is free to rotate on the shaft 15, while the shaft 18 is free to rotate in the bracket 19. Because of differences in thickness of the web, one of the rolls 3 or 4 should be mounted to yield away from the other. In the present instance the printing roll is yieldingly mounted. The yoke body has a laterally extending arm 23 which is connected by a link 24 with one end of a lever 25. This lever 25 is pivoted intermediate its ends on a bracket 26 connected to the support 20 by bolts and nuts 27. A hanger 28 is connected to that end of the lever 25 remote from the printing roll, 75 and this hanger is designed to support a series of weights 29 which are detachable to permit the pressure of the printing roll against the platen roll to be varied. A cable 30 is connected with the lever, for lifting 80 said lever, to swing the printing roll away from the platen roll when desired for any purpose. An oil cup 31 is arranged at the end of the shaft 15, and the lever 25 is supported by a bolt 32. The characters of the 85 dies are flat faced as shown in Figure 5, so that the fibers of the body are not cut, but are displaced and compressed. The characters are raised characters, and of a height corresponding to the depth of the impression 90 desired.

In the operation of making roofing, the felt is passed between the printing roll and the platen roll, where it is impressed with the design. It is then passed through the 100 solution, and between the compressing rollers, which remove the excess solution. Afterwards the protective coating is applied, and rolled by the rollers 10. The compressing rollers are so arranged that the direction 105 of movement of the web is changed as it passed between them, whereby that face of the web which carries the designs is caused to engage one of the rollers over a relatively large area. This extended engagement traps 110 the solution in the impressions, so that it cannot escape in any direction.

Obviously the invention is not limited to any specific form of construction and the details of the illustrative apparatus may be 115 variously modified. Moreover, it is clear that the invention may be employed in different relationships than that herein illustrated. Furthermore, it is not indispensable that all features of the invention be used 120 conjointly inasmuch as they may be employed advantageously in various different combinations and sub-combinations.

Reference is made to my copending application, Serial No. 443,514, in which I 125 claim the article and method herein disclosed.

I claim—

1. In apparatus of the character specified, means for applying a protective coating to 130

one face of a waterproofed web of absorbent material, and means for impressing designs upon the opposite face before the protective coating is applied.

5. 2. In apparatus of the character specified, means for saturating a web or sheet of absorbent material with a waterproofing and adhesive solution, a pair of rollers for expressing the excess solution from the web 10 and arranged so that the direction of movement of the web is changed as it passes between the rollers whereby to cause one face of the web to engage one of the rollers over a relatively large area, and means for impressing designs upon the said face of the web before it is saturated.

3. Apparatus for applying designs or identifying data to a web of relatively soft fibrous material, comprising in combination, 20 means for impressing the designs or the like in one side of the web and means for cementing or fixing the fibers of the web to retain the impressions of the designs.

4. Apparatus for applying designs or 25 identifying data to a web of relatively soft fibrous material, comprising in combination, means for impressing the designs or the like in one side of the web by compressing the web, means for applying a compound to said web, for setting the fibers thereof to retain the impressions, and means for momentarily confining some of said compound under pressure in the impressions of the design to 30 deepen said impressions.

35. 5. Apparatus for applying designs or identifying data to a web of relatively soft fibrous material, comprising in combination, means for impressing the designs or the like in one side of the web, means for cementing 40 or fixing the fibers of the web to retain the impressions of the designs, and means for applying a coating to the other side of the web.

6. In apparatus for treating a web of material of the kind described, the combination

comprising means for applying a preserving compound to said material, means for impressing designs or the like in one side of said web, a roll over which said web passes with the side bearing the impressions against the roll, and means for exerting pressure between the web and said roll whereby the preserving compound in the impressions in said web is placed under pressure, tending to deepen said impressions. 55

7. In apparatus of the character described, the combination comprising, means for impressing designs or the like in a web of fibrous material; means for treating said web with a waterproofing compound; and means through which said treated web passes for removing excess waterproofing compound and cooperating with said web to prevent the obliteration of the impressed designs during removal of the excess waterproofing compound. 60

8. In apparatus of the character described, the combination comprising, means for treating a web of fibrous material with a waterproofing compound; an embossing device for impressing designs or the like in the web before treatment with the waterproofing compound; means for yieldingly pressing together said embossing device and said web; and a roll for removing excess waterproofing compound from said web, said roll being constructed and arranged so that the impressed face of said web contacts with said roll as the web passes over it. 75

9. In apparatus of the character described, the combination with means for applying a preserving compound to a web of material, of means for impressing designs or the like in one face of the web; and means cooperating with said impressed web after 80 the treatment of the web with the preserving compound to prevent obliteration of the impressed designs. 85

In testimony whereof I affix my signature.
ALEXANDER S. SPEER.
